United States Patent Office.

GEORGE W. STRANAHAN, OF WESTPORT, NEW YORK.

Letters Patent No. 99,029, dated January 18, 1870.

IMPROVED WASHING-MACHINE.

The Schedule referred to in these Letters Patent and making part of the same.

To all whom it may concern:

Be it known that I, GEORGE W. STRANAHAN, of Westport, in the county of Essex, and State of New York, have invented a new and useful Improvement in Washing-Machines; and I do hereby declare that the following is a full, clear, and exact description thereof, which will enable others skilled in the art to make and use the same, reference being had to the accompanying drawings, forming part of this specification, in which—

Figure 1 is a vertical cross-section of my improved washing-machine, taken through the line x x , fig. 2.

Figure 2 is a horizontal section of the same, taken through the line y y , fig. 1.

Similar letters of reference indicate corresponding parts.

My invention has for its object to furnish a simple, convenient, and effective washing-machine, which shall be so constructed and arranged that it may be also used as a boiler for heating the water and boiling the clothes; and

It consists in the construction and combination of the various parts of the machine, as hereinafter more fully described.

A is the box or tub of the machine, which is made of tin, copper, or other suitable metal, and which is provided with a cover, **B**, fitting closely upon it, as shown in fig. 1.

C is a shaft, revolving in bearings, in the middle parts of the ends of the tub or boiler **A**, and to the projecting end of which is attached a crank, **D**, for operating the machine.

E is the inner wheel, which is formed by attaching rounds or slats, **e**¹, to disks, **e**².

The tenons of the rounds or slats **e**¹ enter radial slots or grooves in the disks **e**², and are held out to their places by coiled or equivalent springs, **e**³, so as to exert the necessary pressure upon the clothes.

The disks **e**² are also connected by the shaft **e**⁴, which is perforated longitudinally to receive the shaft **C**, encasing said shaft, and preventing the oil and iron rust upon it from coming in contact with the clothes being washed.

F is the outer wheel, the journals or round tenons of the rollers or slats, **f**¹, of which, enter and work in holes or sockets in the disks **f**², through the centres of which disks the shaft **C** passes.

G is a bevel gear-wheel, securely attached to the end of the sleeve **H**, through which passes the shaft **C**, and which passes through the end of the tub or boiler **A**.

Upon the inner end of the sleeve **H** is formed a square tenon, which enters a square hole in the disk **f**², so that the outer wheel **F** may be revolved by the sleeve **H** and gear-wheel **G**, independent of the shaft **C**.

I is a bevel gear-wheel, pivoted to a small frame or bracket, **a**, attached to the end of the tub or boiler **A**.

The teeth of the bevel gear-wheel **I** mesh into the teeth of the bevel gear-wheel **G**, and also into the teeth of the bevel gear-wheel **J**, which revolves loosely upon the shaft **C**.

The bevel gear-wheel **J** may be connected with the shaft **C**, by a pin passing through said shaft, and through a hole in the hub of the said gear-wheel **J**, as shown in fig. 1.

By this arrangement, by revolving the shaft **C** by means of the crank **D**, the wheels **E** and **F** will be revolved at the same time, but in opposite directions.

By removing the pin from the hole in the gear-wheel **J** and shaft **C**, and inserting it in a hole in the frame or bracket **a** and gear-wheel **J**, (said hole is shown in fig. 1,) the gear-wheel **J**, and consequently the outer wheel **F**, will be held stationary, while the inner wheel **E** may be revolved.

The disks **f**² of the wheel **F** have pieces cut out of them, as shown in fig. 1, which pieces are hinged at one end and hooked at their other end to the main bodies of said disks, so that the said pieces, and the slats or rounds **f**¹ attached to them, may serve as a door for the insertion and removal of the clothes.

If desired, the disks **f**² may be made entire, and the ends of the rounds or slats **f**¹ that form the door, attached to curved bars, one end of which are hinged to a round, **f**¹, of the body of the wheel **F**, and their other ends bolted to the disks **f**², or otherwise detachably secured in place.

In using the machine, the clothes to be washed are inserted in the space between the wheels **E** and **F**, and as the said wheels are revolved in opposite directions, the said clothes are swept through the water or suds in the tub or boiler **A**, and at the same time are turned about and rubbed by the action of the wheels **E** and **F**, so as to be thoroughly and quickly washed in all their parts.

Having thus described my invention,

I claim as new, and desire to secure by Letters Patent—

1. The combination of the metallic tub or boiler **A** with the two wheels **E** **F**, constructed as described, and for the purpose set forth.

2. An improved washing-machine, formed by the combination of the two wheels **E** **F**, constructed as described, tub or boiler **A**, shaft **C**, crank **D**, sleeve **H**, and gear-wheels **G** **I** **J**, with each other, substantially as herein shown and described, and for the purpose set forth.

GEO. W. STRANAHAN.
